(57) **CLAIM**

The ornamental design for an electrostatic spray probe, as shown and described.

DESCRIPTION

FIG. 1 is a perspective view of a first embodiment of an electrostatic spray probe;

FIG. 2 is a front elevational view of the first embodiment of the electrostatic spray probe;

FIG. 3 is a rear elevational view of the first embodiment of the electrostatic spray probe;

FIG. 4 is a right side view of the first embodiment of the electrostatic spray probe;

FIG. 5 is a left side view of the first embodiment of the electrostatic spray probe;

FIG. 6 is a top plan view of the first embodiment of the electrostatic spray probe; and,

FIG. 7 is a bottom plan view of the first embodiment of the electrostatic spray probe.

The broken lines are shown for environmental purposes and form no part of the claimed design.
